UNITED STATES PATENT OFFICE.

PETER W. SPRECHER, OF MILWAUKEE, WISCONSIN.

ELECTRIC FIXTURE.

Application filed January 23, 1925. Serial No. 4,210.

To all whom it may concern:

Be it known that I, PETER W. SPRECHER, a citizen of the United States, and resident of Milwaukee, in the county of Milwaukee 5 and State of Wisconsin, have invented certain new and useful Improvements in Electric Fixtures; and I do hereby declare that the following is a full, clear, and exact description thereof.

10 This invention relates to fixtures.

Objects of this invention are to provide a fixture in which a supporting strap carried by the hickey may be secured to a canopy or ceiling collar in a simple and 15 effective manner without requiring any shaping of the canopy or cam action of the strap, but in which the canopy and associated parts are directly carried by the socket and may be easily removed or replaced without disturbing the electrical connections.

Further objects are to provide an electrical fixture in which the canopy is automatically grounded when secured to the 20 socket.

Further objects are to provide a fixture which may be removed or replaced by an unskilled operator and which is so constructed that it is of ornamental and attractive appearance.

An embodiment of the invention is shown in the accompanying drawings, in which:—

Figure 1 is a sectional view through the fixture.

25 Figure 2 is a sectional view on the line 2—2 of Figure 1.

Referring to the drawings, it will be seen that an outlet box 1 is set with its marginal edges flush with the ceiling 2 and that a 30 hickey 3 is secured by means of bolts or other suitable fasteners within the box. This hickey is provided with apertures 4 and 5 for the passage of the wires and is further provided with a downwardly projecting threaded portion 6. A cap 7 is screwed upon the downwardly threaded portion and has an outwardly projecting ear 8 provided with a threaded aperture 9.

A U-shaped strap or supporting member 50 is provided which has a transverse portion 10 and upwardly projecting diverging legs 11 provided with outwardly extending feet 12. An elongated bolt 13 is passed through the transverse portion 10 and is screwed into 55 the threaded aperture 9 thus firmly position-

ing the supporting strap with its feet 12 in contact with the ceiling 2.

A socket 14 is provided and is equipped with a U-shaped clip 15 (see Figure 2) which is secured within a recessed portion 60 of the socket by means of a bolt 16, and such recessed portion is filled with any suitable material, as indicated at 17. The upper portion of the clip 15 is positioned above the transverse portion 10 of the supporting strap. Preferably, the supporting strap is made of wrought iron or structural steel and is provided with a brass bushing 18 (see Figure 2). This bushing is provided with a threaded aperture into which an attaching screw 19 passes, such screw securing the clip 15 in place (see Figure 2). It is to be noted upon further reference to Figure 2 that a spring or grounding member 20 is also retained beneath the head of 75 the screw 19.

Referring to Figure 2, it will be seen that the socket is provided with a threaded shell 21 in the usual manner adapted to receive the lamp. The outer sleeve 22, preferably 80 formed of porcelain or other insulating material is screwed upon the exterior of the threaded sleeve 21, as shown in Figure 2, and is provided with an enlarged lower portion 23, preferably equipped with a 85 roughened or fluted lower conical face 24, as shown in Figure 1. This enlarged portion has a flat face or shoulder 25 on the upper side of the enlarged portion 23.

Any suitable type of canopy or sealing collar member may be employed, and for assembling, the canopy may conveniently be formed of two parts 26 and 27 adapted to respectively contact with the ceiling 2 and with the shade or globe 28. These portions 95 of the canopy may be joined by inwardly extending flanges 29.

In assembling the device, the cap 7 is screwed in place and the attaching strap secured by means of the bolt 13, as previously described. The socket is securely held to the transverse portion of the supporting strap. The canopy is slipped in place, and the outer sleeve 22 is screwed upon the threaded shell 21 of the socket, with the shoulder 25 engaging the under side of the inwardly extending flange 29 of the canopy.

It will be seen, therefore, that no cooperating cam faces need be provided be- 110

tween the supporting strap and the canopy and that no additional screws, pins or plungers need be employed for retaining the canopy in position. It is easily and securely retained in position by the outer sleeve 22 of the socket.

It is to be particularly noted from reference to Figure 2 that the canopy or fixture is ground by means of the grounding spring 20 in an automatic manner for the reason that the spring presses outwardly due to its inherent resiliency and slides along the inside of the canopy while such canopy is being positioned, thus insuring a secure and perfect grounding of the canopy without any attention whatsoever on the part of the electrician.

It is also to be noted that this fixture may be most readily cleaned and that the canopy and globe may be most easily removed by an unskilled operator without disturbing any of the electrical connections. For example, it is merely necessary to remove the globe 28 and, thereafter, unscrew the outer sleeve 22 by manipulating the enlarged lower portion 23 thereof,—the fluted portion 24 on the lower side or part of the sleeve affording a secure grip for the operator's fingers. The parts may be readily washed or otherwise cleaned and easily replaced.

It will thus be seen that a fixture has been provided which may be most easily assembled, in which the exposed parts may be readily taken down for cleaning and as easily replaced.

Further, it will be seen that there are no fragile or complicated parts to the fixture but that all of the parts are relatively strong.

While I have shown the plug shell 4 attached to the U-shaped strip 10 by means of a screw 6, I may vary this means of attachment.

Although the invention has been described in considerable detail, it is to be understood that the invention may be variously embodied and is, therefore, to be limited only as claimed.

50 I claim:

1. An electric fixture comprising a cap, a supporting strap having a transverse lower portion and a pair of upwardly extending arms adapted to contact with a wall surface, a screw extending through said transverse

portion and screwed into said cap, a socket carried by said transverse portion and having an outer shell removably screwed on said socket, and a canopy surrounding said supporting strap and held in place by the removable shell of said socket.

2. An electric fixture comprising a cap, a supporting strap having a transverse lower portion and a pair of upwardly extending arms adapted to contact with a wall surface, a screw extending through said transverse portion and screwed into said cap, a socket carried by said transverse portion and having an outer shell removably screwed on said socket, a canopy surrounding said supporting strap and held in place by the removable shell of said socket, and a grounding spring carried by said strap and adapted to contact with said canopy.

3. An electric fixture comprising a cap, an inverted U-shaped strap having outwardly extending feet positioned upon opposite sides of said cap, an elongated screw passing through said strap and screwed into said cap, a socket secured to the lower portion of said strap and having an externally threaded portion, a canopy surrounding said strap and socket and having an inturned flange, and an internally threaded sleeve screwed upon said socket and having an outwardly extending flange engaging the flange of said canopy and holding said canopy in place.

4. An electric fixture comprising a cap, an inverted U-shaped strap having outwardly extending feet positioned upon opposite sides of said cap, an elongated screw passing through said strap and screwed into said cap, a socket secured to the lower portion of said strap and having an externally threaded portion, a canopy surrounding said strap and socket and having an inturned flange, an internally threaded insulating sleeve screwed upon said socket and having an outwardly extending flange engaging the flange of said canopy and holding said canopy in place, and a grounding spring secured to said strap and frictionally engaging said canopy.

In testimony that I claim the foregoing I have hereunto set my hand at Milwaukee, in the county of Milwaukee and State of Wisconsin.

PETER W. SPRECHER.
